UNITED STATES PATENT OFFICE.

GEORGE W. WRIGHT, OF DEMING, NEW MEXICO.

PROCESS OF AND APPARATUS FOR SMELTING ORES.

1,211,805.

Specification of Letters Patent.

Patented Jan. 9, 1917.

Application filed July 25, 1916. Serial No. 111,146.

To all whom it may concern:

Be it known that I, GEORGE W. WRIGHT, a citizen of the United States of America, a resident of Deming, in the county of Luna, 5 State of New Mexico, have invented certain new and useful Improvements in Processes of and Apparatus for Smelting Ores, of which the following is a full, clear, and exact description, reference being had to 10 the accompanying drawings, forming a part of this specification.

My invention relates to a method of and means for obtaining metal from zinc ore.

Prior to this invention zinc ore, mixed 15 with carbon, has been placed in small retorts, the latter being sealed to exclude air from the interior thereof, and the retorts have been subjected to intense heat for a period of about twenty or twenty-four 20 hours. The vapor rising from the ore in each sealed retort is conducted to a condenser where it is converted into molten zinc. Actual experience has shown that molten zinc begins to accumulate in the condenser after the retort has been heated for 25 about 30 minutes, and in about $2\frac{1}{2}$ or 3 hours 50% to 60% of the metal is removed from the zinc ore. At this time the carbon in the sealed retort is in such a condition 30 that the fumes cannot circulate freely from the ore, and it has been found necessary to continue the distilling operation for about 20 hours longer to remove the zinc from the mixture in the retort. The zinc smelters 35 now in general use are so constructed that the supply of carbon cannot be replenished during the smelting operation, and the zinc ore cannot be stirred or agitated to facilitate the distillation of the zinc, this being 40 due to the fact that the small retorts are sealed to exclude air, and it would be impracticable and very undesirable to open them during the smelting operation. The cost of heating the retorts for a period of 45 20 or 24 hours is of course very great, and the metal is impaired by the action of the intense heat. However, this is the ordinary practice which has been generally adopted and followed for a great number of years.

50 Realizing that the molten zinc will begin to appear in the old apparatus in about 30 minutes and that 50% to 60% of the zinc is recovered in about $2\frac{1}{2}$ or 3 hours, one of my objects is to produce an apparatus having 55 its elements so constructed and arranged that the rapid distillation and condensation

may be obtained constantly during the smelting operation. Obviously, this will result in a marked saving of fuel; the quality of the metal will not be impaired by the heat 60 to which it is subjected for a comparatively brief period of time, and a very large percentage of the metal will be recovered from the ore. Heretofore, only about 85% of the metal has been obtained from the ore. To 65 accomplish these results, the retort must be closed to exclude air therefrom, and the new apparatus preferably includes means for feeding ore and carbon into the closed retort, means for stirring the material in the 70 retort, and other details of construction which will be hereinafter described. At the beginning of the operation ore mixed with carbon is fed into the retort and the action may be observed by looking through 75 sight openings in the retort and the condenser. When the action of the apparatus is retarded, the ore may be stirred without opening the closed retort and the supply of carbon, etc., may be replenished without 80 opening the retort. Hence, the highest efficiency may be obtained at all times, and almost all of the zinc may be recovered without subjecting the ore to an intense heat for 85 a long period of time.

With the foregoing and other objects in view the invention comprises the novel construction, combination and arrangement of parts hereinafter more specifically described and illustrated in the accompanying drawings 90 wherein is shown the preferred embodiment of the invention; however, it is to be understood that the invention comprehends changes, variations and modifications which come within the scope of the claims hereunto 95 appended.

Figure I is a longitudinal section of a zinc smelting apparatus constructed in accordance with my invention. Fig. II is an enlarged fragmentary section showing the 100 retort, the feeding device and one of the agitators. Fig. III is a vertical section on line III—III, Fig. I. Fig. IV is a front elevation partly in section. Fig. V is an enlarged fragmentary section showing the outer end 105 of one of the inspection tubes.

A designates a retort communicating with a condenser B, a low wall 1 (Fig. I) being formed between the retort and condenser. A chamber 2 located below the retort may 110 be provided with any suitable means for heating the retort. Since the retort is sub-

jected to a very intense heat, its bottom, side and top walls are preferably made of carborundum, such material being very strong and capable of withstanding a high 5 degree of heat. The front wall 3 of the retort is preferably a cast iron member provided with a water jacket. 4 designates long rods connecting the front wall 3 to the condenser. Springs 5 are arranged between 10 heads on the rods 4 and flanges on the condenser to compensate for the expansion and contraction of the retort.

The condenser B has an opening 6 (Fig. I) for the discharge of inflammable gases 15 which pass from the interior of the condenser. A receptacle 7 (Fig. I) is arranged below a discharge opening 9 to receive the molten metal flowing from the condenser.

10 designates a discharge pipe leading 20 from the receptacle 7. A fluid conducting pipe 11, extending into the condenser, terminates in an ejector nozzle 12 which lies adjacent to the discharge opening 6. Steam, air or other fluid may be discharged through 25 the nozzle 12 for a purpose which will be hereinafter described.

Tubular members 13, extending from various parts of the apparatus, are provided with sight openings through which the action 30 in the retort, condenser and discharge receptacle may be observed. To prevent the admission of air, these sight openings are closed by transparent members 14, (Fig. V) made of mica or other heat resisting material. Each tubular member 13 is also provided with a valve 15 which may be closed to exclude the air when one of the transparent members is accidentally broken.

The agitators for stirring the contents of 40 the retort are preferably in the form of rakes E having hollow teeth which communicate with the long hollow operating handles 16. Each operating handle comprises an outer tube and an inner tube (Fig. 45 II) through which water may be circulated for the purpose of cooling the rakes.

17 designates flexible water conducting pipes (Fig. I) leading from these inner and outer tubes.

50 The rake handles 16 extend through flexible tubes 18, the inner end of each tube 18 being secured to the front wall of the retort, and the free outer end being provided with a stuffing box 19. The rake handles are free 55 to slide in the stuffing boxes and the flexible tubes 18 are free to move in any direction. It will be noted that the tubes 18 and their stuffing boxes constitute universal bearings for the rake handles, allowing the rakes to 60 be moved in any direction by operating their handles at the exterior of the retort. 20 designates recesses formed in the inner face of the front wall 3 and adapted to receive the rakes E.

65 The combined feeding device and closure

comprises a cylindrical piston 21 slidably mounted in the cylindrical housing 22, and adapted to be moved from the position shown in Fig. I to the position shown in Fig. II for the purpose of conducting ore, 70 carbon and other material into the retort. A slot 23, (Fig. IV) formed in the cylindrical piston 21, registers with the discharge opening of a receptacle 24 when the piston occupies the position shown in Fig. I. The 75 ore, carbon, etc., contained in the receptacle 24 may be discharged through the slot 23 in the piston and carried into the retort A, as shown in Fig. II. Thereafter, the piston may be turned one-half of a revolution to 80 allow the material to fall through the slot 23 and onto the bottom wall of the retort. This material may then be distributed by operating the rakes E. It will be noted that the cylinder 22 forms a continuation of the inlet 85 opening through which the material is conducted into the retort. When the parts occupy the positions shown in Fig. I, a head 25 at the inner end of piston 21, closes the inlet to exclude air from the interior of the 90 retort. When the parts are shifted to the position shown in Fig. II, an intermediate head 26 will prevent the admission of air from the interior of the piston 21 to the retort. The piston is closely fitted to the cylinder, 95 said piston serving as a valve for closing the discharge opening of receptacle 24 when the parts occupy the positions shown in Fig. II.

27 designates a piston housing, extending 100 from the cylinder 22 and provided with a stuffing box 28 in which a piston rod 29 is slidably mounted. This piston rod comprises an inner tube and an outer tube (Fig. II) through which water may circulate and 105 flow through the water jacket in the closure member 25.

30 designates flexible water conducting tubes leading from the inner and outer tubes of the piston rod 29, as shown in Fig. II. A water jacket 31 is preferably formed around the cylindrical housing member 22.

The retort A has a discharge opening 32 (Fig. III) through which the residue may be withdrawn, said opening being normally 110 closed by a door 33, shown in Figs. III and IV.

In using the apparatus I have shown, zinc ore mixed with carbon is introduced into the receptacle 24 and conducted into the retort by the feeding device. This material soon becomes very hot and the vapor rising therefrom flows into the comparatively cool condenser, where it liquefies and passes into discharge receptacle 7. This liquid is molten zinc. Some liquid will also form in the retort and flow through openings 34 (Fig. I) at the lower edge of wall 1. The floor of the condenser B slopes toward the discharge opening 9 and all of the liquid just referred 120 125 130

to will, therefore, flow through said opening. The operator may observe the condition and quantity of the material in different parts of the apparatus by looking through the inspection tubes 13, and the material in the retort may be stirred whenever necessary by actuating the rakes E, thereby exposing all of the ore directly to the heat of the bottom wall of the retort. The supply of carbon may be easily replenished by feeding carbon from the receptacle 24 to the closed retort. By stirring the material and supplying additional carbon occasionally, the zinc will vaporize very rapidly, and to provide for the required rapid condensation, the condenser is larger than the retort. When it becomes necessary or desirable to condense the fumes or vapor more rapidly, the ejector 12 may be utilized to increase the rate of flow at the gas outlet 6, and the action of the ejector may be controlled by regulating the valve in the pipe 11.

Obviously, the distilling and condensing operations will take place very rapidly, thus economizing in the use of fuel and time, and the metal will not be injured by long exposure to the intense heat of the apparatus. Moreover, the operations may be carried out continuously by feeding ore and carbon into the closed retort occasionally, until it becomes necessary to remove the residue through the opening 32.

I claim:—

1. A smelting apparatus comprising a retort, an agitator arranged in said retort, said agitator being provided with an operating device which extends through a wall of the retort, and means for closing said retort to exclude air from the interior thereof, said means including a universal bearing in which said operating device is slidably mounted.

2. A smelting apparatus comprising a retort, an agitator arranged in said retort, said agitator being provided with an operating device which extends through a wall of the retort, and means for closing said retort to exclude air from the interior thereof, said means including a flexible tube surrounding a portion of said operating device and a stuffing box at the free outer end of said flexible tube.

3. A smelting apparatus comprising a retort, means for closing said retort to exclude air from the interior thereof, said retort having an inlet, a feeder provided with a closure for said inlet, and a housing closely fitted to said feeder, said feeder being movable into the closed retort and said closure being movable with the feeder.

4. A smelting apparatus comprising a retort, means for closing said retort to exclude

air from the interior thereof, said retort having an inlet, a feeder provided with means for closing said inlet, a housing to which said feeder is closely fitted, and a receptacle having a discharge opening through which material may be discharged to said feeder, said feeder being movable through said inlet to feed the material into the closed retort. 70

5. A smelting apparatus comprising a retort, means for closing said retort to exclude air from the interior thereof, said retort having an inlet and a feeder housing forming a continuation of said inlet, a feeder provided with means for closing said inlet, said housing having an inlet for the admission of material to said feeder, the latter having a pocket open at the top to receive said material and said feeder being adapted to reciprocate in said housing so as to carry the material into the closed retort and also adapted to turn in the housing to discharge the material in the retort. 85

6. A zinc smelting apparatus comprising a retort, means for closing said retort to exclude air from the interior thereof, a feeding device arranged to feed material into the closed retort, and an agitator arranged within the closed retort to stir the material therein. 90

7. A smelting apparatus comprising a retort, a feeder movable into said retort to feed the material thereto, and a water jacket 95 at the inner end of said feeder.

8. A smelting apparatus comprising a retort, a condenser, means for closing said parts to exclude air therefrom, the condenser being provided with a discharge 100 opening, and an ejector for forcing gas through said discharge opening.

9. A zinc smelting apparatus comprising a retort, a condenser, the condenser being larger than the retort, and an ejector for 105 discharging gases from said condenser.

10. The method of smelting zinc which comprises introducing zinc ore and a reducing agent into a retort and stirring the same from time to time. 110

11. The method of smelting zinc which comprises introducing zinc ore and a reducing agent into a retort, partially distilling the zinc, then adding a reducing agent to the partially distilled zinc, and stirring the mixture in the retort. 115

12. The method of smelting zinc which comprises confining zinc ore and a reducing agent in a closed retort, partially distilling the zinc, then introducing an additional supply of reducing agent into the closed retort, and stirring the mixture confined in the closed retort. 120

GEORGE W. WRIGHT.
